UNITED STATES PATENT OFFICE.

MAHLON E. LAYNE AND SAMUEL N. HALL, OF LOS ANGELES, CALIFORNIA; SAID HALL
ASSIGNOR TO SAID LAYNE.

WELL MECHANISM.

1,415,586.

Specification of Letters Patent. Patented May 9, 1922.

Application filed September 8, 1920. Serial No. 408,943.

To all whom it may concern:

Be it known that we, MAHLON E. LAYNE and SAMUEL N. HALL, both citizens of the United States, residing at Los Angeles, in 5 the county of Los Angeles and State of California, have invented certain new and useful Improvements in Well Mechanism, of which the following is a specification.

The invention relates to well mechanism 10 and particularly to rotary or centrifugal pump mechanism involving the use of a pump placed in or adjacent the water of a well and transmission and discharge mechanism extending to the surface of the ground. 15 The invention has for its primary objects: (1) the provision of improved means for packing the pump casing in the well casing; (2) the provision of means whereby the packing can be adjusted and tightened 20 from the surface of the ground; (3) the provision of packing means of the type specified which can be applied at the upper portions of the pump casing so that it can be applied to a multi-stage pump without providing pockets for the accumulation of sand 25 between the pump and well casings which would tend to prevent the ready removal of the pump for replacement or repair; and the provision of a packing means which 30 does not prevent the suspension of the pump from the discharge and shaft casings whereby such casings are subject to tension tending to hold them straight. Certain embodiments of the invention are illustrated in the 35 accompanying drawings, wherein—

Fig. 1 is an assembly view largely in a vertical section showing the application of the improvement to a pump. Fig. 2 is an enlarged partial vertical section and partial 40 elevation taken through the apparatus to which the improvement is applied. Fig. 3 is an enlarged vertical section showing one form of coupling which may be employed. Fig. 4 is a transverse section at IV—IV of 45 Fig. 3, and Fig. 5 is a vertical section through a modified form of coupling which may be employed.

Referring first to the general arrangement the principal parts of the pump may be 50 enumerated as follows: 1 is the pump casing carrying the runners or impellers 2 keyed to the drive shaft 3; 4 is the well casing which also acts as a discharge casing and extends to the surface of the ground, 55 discharging through the lateral outlet 5; 6

is the shaft casing extending from the pump neck to the platform 7 at which point it is connected to the casting 8 by means of a coupling 9; 10 are leaf springs for preventing the pump from turning in the well casing; and 11 is the drive pulley by means of which the shaft 3 is driven.

The feature to which the invention is particularly directed is shown in Fig. 2 and comprises the improved means whereby the 60 pump casing is packed with respect to the casing 4 so that such casing may act as a discharge casing as well as a well casing. The arrangement is such that the packing may be tightened or loosened by rotation of 65 the shaft casing, a nut being swiveled upon the lower end of the shaft casing and connected to the gland or presser member of the packing device so that such presser means may be moved up and down. This 70 packing device is arranged adjacent the upper end of the pump casing so that no pocket is formed between the pump casing and the well casing and there is no opportunity for a deposit of sand or dirt between the casings such as is the case where a pump is 75 packed by allowing it to rest upon a packing device at the bottom of a well casing; this latter construction rendering the pump difficult of removal after the space has been 80 filled with sand or dirt, particularly with a multi-stage pump. The arrangement also permits the main portion of the weight of the pump and the column of water above it to be suspended from the shaft casing 6, 85 thus tending to keep it straight, which is not the case in a construction in which the weight of a pump is supported by setting the pump upon the bottom of a well. The 90 present construction is, therefore, applicable 95 to multi-stage pumps and deep well work.

A seat 12 is provided adjacent the upper portion of the pump casing which seat carries the packing 13. This packing may be of rubber or any other suitable composition 100 and is forced down by the presser member or gland guided on the stud bolts 15 extending through the packing for withdrawing it. The casing is also provided with a pair of lugs 16 to prevent the rotation of 105 the gland 14, such lugs being adapted to engage the arms 17 by means of which the gland is pressed down. The arms are placed at spaced intervals around the circumference of the gland and connecting at their 110

inner ends internally threaded sleeve 18. The sleeve 18 is threaded to the sleeve 19 which in turn is secured by the bolts 20 to the sleeve 21. In order to keep the water 5 and sand from working in between the sleeve 18 and the sleeve 19 the packing 22 is provided, held in place by the collar 23.

The sleeve 21 is bolted at its upper end to the coupling member 24 by means of the 10 bolts 25 and the coupling member 24 together with the externally threaded bearing 26 serves to secure the sleeve 21 to the lower end of the shaft casing 6. To prevent the lower end of the shaft casing 6 unscrewing 15 a split tapering sleeve 27 is employed, such sleeve being driven tightly into a recess between the sleeve 24 and the shaft casing 6 as indicated in the drawing. It will be seen that the sleeve 21 forms in effect a continuation 20 of the shaft casing and that such section is swiveled in the hollow casting 28 forming the inner part of the pump casing, the extreme lower end of the sleeve 21 being turned outwardly as indicated at 29. Brass 25 bushings 30 and 31 are employed between the member 28 and lower end of the sleeve 21 so as to prevent sticking such as would occur if the iron of the member 28 came directly in contact with the iron sleeve. 30 Packing 32 is also provided above the bushing 30 in order to keep out sand and water.

In assembling the apparatus after the well casing has been installed, the pump is lowered to its desired position supported by 35 the shaft casing 6, the sleeve 18 which carries the gland being screwed up at such time so that there is no pressure on the packing 13. When the pump reaches the proper level in the casing, a proper turning tool, such as 40 a pipe wrench, is applied to the upper end of the shaft casing and it is rotated to screw the sleeve 18 downward, thus carrying the gland 14 downward against the packing and compressing it laterally so as to form a sealing 45 joint between the casing 4 and the pump. When it is desired to remove the pump from the well for replacement or repair of any of its parts, the shaft casing is rotated backwardly thus causing the sleeve 18 to move 50 upward and release the packing, after which the pump may be pulled from the well in the usual way. In case the shaft casing 6 should become broken it would still be possible to loosen the packing by lowering an 55 internally threaded sleeve and causing it to engage the threaded surface 33 of the coupling member 24, after which the sleeve 21 could be rotated to loosen the packing. A suitable bearing in the pump neck is provided 60 in the form of the brass or composition member 34, which may be of any desired construction.

In order to prevent the shaft casing from unscrewing where its sections are jointed together, the types of couplings shown in Figs.

3 and 5 may be employed. The coupling shown in Fig. 3 comprises a split sleeve member 35 clamped in position by the bolt 36 and sawed laterally and vertically as indicated at 37 and 38 so as to give the necessary flexibility to the coupling to permit it being clamped in position.

In the construction of Fig. 5 the coupling 39 is either riveted in place at one end as indicated at 40 or spot-welded, while the 75 upper portion is provided with a tapering recess adapted to receive the split tapering wedge 41, which is either tightly driven or screwed into position. Couplings of the foregoing types serve to permit the casing 80 to be rotated in order to adjust the gland for packing the pump up and down, considerable force being required in some cases to accomplish this result so that very secure connections at the joints of the shaft casing 85 are necessary.

What we claim is:

1. In combination in a well mechanism, a combined well and discharge casing, a pump in the casing, a drive shaft extending 90 upward therefrom, a shaft casing provided with bearings for the shaft, a packing between the upper portion of the pump and said well and discharge casing, and means operable from the surface of the ground for 95 tightening said packing after the pump has been set.

2. In combination in a well mechanism, a combined well and discharge casing, a pump in the casing, a drive shaft extending 100 upward therefrom, a shaft casing provided with bearings for the shaft, an annular seat on the pump, packing on said seat between the pump and said well and discharge casing, a gland above said packing, and means 105 operable from the surface of the ground for operating said gland.

3. In combination in a well mechanism, a combined well and discharge casing, a pump in the casing, a drive shaft extending 110 upward therefrom, a shaft casing provided with bearings for the shaft, a packing between the upper portion of the pump and said well and discharge casing, and means operable by the movement of the shaft casing 115 for tightening said packing.

4. In combination in a well mechanism, a combined well and discharge casing, a pump in the casing, a drive shaft extending 120 upward therefrom, a shaft casing provided with bearings for the shaft, a packing between the upper portion of the pump and said well and discharge casing, and means operable by the rotation of the shaft casing for tightening said packing.

5. In combination in a well mechanism, a combined well and discharge casing, a pump in the casing, a drive shaft extending upward therefrom, a shaft casing provided with bearings for the shaft, a packing be- 130

- between the upper portion of the pump and said well and discharge casing, a presser member for compressing said packing, a threaded member connected to the presser member and a threaded sleeve carried by the shaft casing and engaging said threaded member whereby the rotation of the shaft casing moves the presser member up and down.
- 10 6. In combination in a well mechanism, a combined well and discharge casing, a pump in the casing, a drive shaft extending upward therefrom, a shaft casing provided with bearings for the shaft and movable in a rotary direction about its axis, packing between the pump and the well and discharge casing, and a presser member for the packing having screw engagement with the shaft casing and adapted to be moved up and down by the rotation thereof.
7. In combination in a well mechanism, a combined well and discharge casing, a pump in the casing, a drive shaft extending upward therefrom, a shaft casing provided with bearings for the shaft and movable in a rotary direction about its axis, packing between the pump and the well and discharge casing, and a presser member for the packing and held against rotation, and screw engaging means between the presser member and shaft casing whereby the rotation of the shaft casing moves the presser member up and down.
8. In combination in a well mechanism, a combined well and discharge casing, a pump in the casing, a drive shaft extending upward therefrom, a shaft casing provided with bearings for the shaft and movable in a rotary direction about its axis, packing between the pump and the well and discharge casing, a presser member for the packing having screw engagement with the shaft casing and means for holding the presser member against rotation whereby the rotation of the shaft casing moves the presser member up and down.
- 15 9. In combination in a well mechanism, a combined well and discharge casing, a pump in the casing, a drive shaft extending upward therefrom, a shaft casing provided with bearings for the shaft, a packing between the pump and said well and discharge casing, means operable by the rotation of the shaft casing for tightening said packing, and yielding means between the pump and the well and discharge casing for holding the pump against rotation when the shaft casing is rotated.
- 10 10. In combination in a well mechanism, a combined well and discharge casing, a pump in the casing, a drive shaft extending upward therefrom, a shaft casing provided with bearings for the shaft, a packing between the pump and said well and discharge casing, means operable by the rotation of the shaft casing for tightening said packing, and spring means carried by the pump and engaging the well and discharge casing for preventing the rotation of the pump when the shaft casing is rotated.
